UNITED STATES PATENT OFFICE.

ALBERT HAGER AND PAUL SEHRIG, OF WEST HOBOKEN, NEW JERSEY.

STOCKING HOLDER FOR EMBROIDERY MACHINES.

Application filed August 8, 1922. Serial No. 580,394.

To all whom it may concern:

Be it known that we, ALBERT HAGER and PAUL SEHRIG, both citizens of the United States, and residents of West Hoboken, in the county of Hudson and State of New Jersey, have invented a certain new and useful Improvement in Stocking Holders for Embroidery Machines, of which the following is a specification.

10. This invention relates to a stocking supporting device for embroidery machines and has for its primary object to provide a very simply constructed device of this character which will support or hold a completed stocking in open tubular form while it is being embroidered.

Heretofore, in the operation of automatic embroidery machines of that type wherein a plurality of stockings or like articles are 20 simultaneously embroidered, the position of the stocking material relative to the needles being controlled by means of a pantograph mechanism, the embroidery is applied while the stocking is in an intermediate stage of 25 its manufacture, or in other words, when it is in the form of a flat single thickness of material. By means of the present invention, it is possible to first complete the manufacture of the stocking and then subsequently, with the stocking supported in tubular form, apply the ornamental embroidery in the desired design to one side thereof.

As one exemplification of our present invention, we have selected a very simple and 35 practical construction of the stocking holder or supporter. Briefly, the same consists of an elongated tubular sheet metal structure open upon one side and provided with means at one end whereby the holder or supporter can be conveniently mounted upon an actuator bar whereby the holder is manipulated relative to the needle in the execution of the design. Within the stocking supporter a shuttle holder is positioned, the 40 needle operating at the open side of the holder in cooperative relation with the reciprocating shuttle so as to properly form the thread stitches through the stocking material.

50. With the above and other objects in view, the invention consists in the improved stocking holder or supporter, and in the form, construction and relative arrangement of its several parts as will be herein-after more fully described, illustrated in the

accompanying drawing and subsequently incorporated in the subjoined claims.

In the drawing wherein we have disclosed a desirable embodiment of the invention and in which similar reference characters 60 designate corresponding parts throughout the several views,

Figure 1 is a side elevation of the stocking supporter, the shuttle holder being illustrated in dotted lines;

Figure 2 is a longitudinal section taken on the line 2—2 of Figure 1; and

Figure 3 is a section taken on the line 3—3 of Figure 1.

The device as illustrated in the accompanying drawing is preferably, though not necessarily, formed from sheet metal and may be conveniently produced in a single stamping operation to provide a rear or back wall 5, and longitudinally extending 70 obliquely arranged parallel side walls of different lengths connected by an end wall 7. The free edges of the walls 6 and 7 are preferably turned inwardly to provide the reinforcing bead 8. The wall 7, which, 80 when the device is in use, is located at the upper end of the holder, may be of any desired shape or form and at the opposite end of the holder the reinforced edges of the side walls 6 are connected and braced by 85 means of a cross strap 9. The lower end edge of the rear wall 5 is disposed at an oblique angle with respect to the side walls 6 and the brace bar or strap 9 is disposed in parallel relation therewith. To this lower end of the rear wall 5 spaced supporting pins 10 are rigidly fixed and are adapted to be engaged in sockets in an actuator bar of the embroidery machine (not shown) or otherwise removably mounted in said bar. 90 A battery of these stocking holders or supporters are arranged in spaced relation upon the actuator bar and are adapted to be simultaneously moved or shifted when said bar is operated by a pantograph mechanism, which in turn, is actuated in accordance with the design pattern.

In Figure 2 of the drawing we have shown one of the embroidery needles 11 in dotted lines. As the needle operating mechanism constitutes no part of my present invention, it is not herein disclosed. For the purposes of this explanation, it will suffice to state that one of said needles is located at the open side of each of the stocking hold-

ers or supporters and co-operates with a reciprocating thread carrying shuttle of conventional design which is mounted in the shuttle holder 12 arranged upon the upper 5 end of the rod or support 13 extending longitudinally within the stocking holder.

From the foregoing description, the operation of the device will be obvious. The stocking is first stretched downwardly over 10 and upon the holder or supporter with the side thereof to which the embroidery is to be applied extending over the open side of the holder. The holder or support maintains the stocking material perfectly smooth 15 and without wrinkles. After each one of the battery of holders has been supplied with a stocking, in the operation of the machine, these holders are shifted relative to the associated series of needles 11 which 20 are simultaneously actuated and reciprocate back and forth through the stocking material, said needles with their threads being supplied with thread by the reciprocating shuttles in the well known manner 25 whereby the embroidery stitches are properly formed in the material to produce the preconceived design.

By the use of our present invention it will be seen that the application of clock-work or embroidery to stockings may be accurately executed after the manufacture 30 of the stocking itself has been fully completed.

It is accordingly to be understood that 35 while we have herein described our present device in more or less detail, it may in certain instances, be found desirable to construct the stocking supporter or holder in other forms, shapes and sizes. It is, therefore, to be understood that as the invention 40 may be incorporated in other alternative structures, we reserve the privilege of resorting to all such legitimate changes or modifications therein as may be fairly embodied within the spirit and scope of the 45 invention as claimed.

We claim:

1. In combination with a needle and shuttle holder of an embroidery machine, an elongated hosiery supporting member having a back wall, marginal side walls, an end wall, and an open front, said back wall being provided with means whereby said member may be mounted on a movable 55 part of the machine with a shuttle holder disposed between said marginal side walls, said member being adapted to support hosiery in tubular form with one side thereof extending over the open front of said member between the shuttle holder and the needle.
2. In combination with a needle and shuttle holder of an embroidery machine, an elongated hosiery supporting member hav-

ing a back wall, marginal side walls, an end 65 wall, and an open front, said back wall being provided with means at one end whereby said member may be mounted in a movable part of the machine with a shuttle holder disposed between said marginal side 70 walls and a re-enforcing connection extending between the longitudinal edges of said side walls at one end of the supporting member, said member being adapted to support hosiery in tubular form with one side 75 thereof extending over the open front of said member between the shuttle holder and the needle.

3. In combination with the stitching mechanism of an embroidery machine, a 80 detachable stretcher frame having a back wall, an end wall and side walls extending laterally from the back wall, forming an open front, and supporting means connected with one end of said frame.

4. An embroidery frame for finished hosiery having a back, an end wall, and side walls extending laterally from said back, forming an open front, and supporting means connected with one end of said 90 frame.

5. An embroidery frame for finished hosiery having a back, an end wall, and side walls of unequal length extending laterally from said back, forming an open front, and supporting means connected with one 95 end of said frame.

6. An embroidery frame for finished hosiery having a back inclined at its lower 100 end relative to its lateral margins and provided with supporting pins, an end wall and side walls extending laterally from said back, forming an open front, and a cross bar connecting the lower outer margins of said side walls in parallel relation with the 105 lower margin of said back.

7. An embroidery frame for finished hosiery, comprising an obliquely arranged back having laterally extending side walls of unequal lengths and having a horizontally arranged lower end and an obliquely arranged upper end and supporting pins carried by the horizontally arranged lower end.

8. An embroidery frame for finished 115 hosiery, comprising a back obliquely arranged and having laterally extending side walls of unequal lengths forming a frame with an open obliquely arranged front, said frame having a horizontally arranged lower 120 end and an obliquely arranged upper end and supporting pins carried by the horizontally arranged lower end.

In testimony that we claim the foregoing as our invention, we have signed our names 125 hereunder.

ALBERT HAGER.
PAUL SEHRIG.
